Patented Nov. 4, 1958

183,823

TOY SAVINGS BANK

John Berzac, St. Clair Shores, Mich.

Application November 18, 1957, Serial No. 48,522

Term of patent 14 years

(Cl. D34—11)

Fig. 1 is a right side elevational view of a toy savings bank showing my new design;

Fig. 2 is a left side elevational view of the bank shown in Fig. 1;

Fig. 3 is a front elevational view of the bank shown in Figs. 1 and 2; and,

Fig. 4 is a lower end plan view of the bank shown in Figs. 1, 2 and 3.

I claim:

The ornamental design for a toy savings bank, substantially as shown.
